UNITED STATES PATENT OFFICE

THEODORE WILLARD CASE, OF AUBURN, NEW YORK, ASSIGNOR TO CASE RESEARCH LABORATORY INCORPORATED, OF AUBURN, NEW YORK, A CORPORATION OF NEW YORK

METHOD AND APPARATUS FOR TRANSMITTING PICTURES

Application filed August 25, 1925. Serial No. 52,381.

This invention relates to a method and apparatus for transmitting pictures, motion-pictures, or direct vision over either radio or wire.

5 The main object of the invention is the production of a method and apparatus by means of which pictures, motion-pictures or direct vision can be transmitted in an efficient and satisfactory manner by either radio or wire.

10 Other objects and advantages relate to the details of the method and apparatus, all as will more fully appear from the following description taken in connection with the accompanying drawings, in which:—

Figures 1, 2 and 3 are diagrammatic illustrations of embodiments of this invention.

The transmitting apparatus of Figure 1 includes a bulb —1— of glass or similar material, preferably having a substantially flat end 2. The bulb 1 encloses a filament 3 adapted to be heated in any suitable manner, as by a source of potential 4 and the filament is connected in circuit with a metal cylinder 5 located within the bulb 1 and adjacent the filament, but as here shown, separated from it by a disk 6 having a relatively small opening aligned with the apex of the filament and with the conduit through the cylinder 5, such 20 circuit including a source of potential.

Within the bulb 1 and above the cylinder 5 are two plates 7 parallel to each other so that electrons emitted by the filament and passing thru the cylinder 5 will also pass 25 between the plates 7. Above the plates 7 there is placed another pair of plates 8 parallel to each other and disposed at substantially right angles to the plates 7 and so positioned that the stream of electrons emitted by the filament and passing through the cylinder 5 and between plates 7 will also 30 pass between the plates 8.

As shown, one plate of each pair is electrically connected to the cylinder 5. The end 45 2 of the bulb or bottle 1 has a coating 9 in the form of a semi-transparent or opaque layer of some conducting photo-electric material, such as potassium or any material which emits electrons under the influence of light.

50 A substantial vacuum is maintained within

the bulb 1 altho it should be understood that the vacuum may not be the highest obtainable as a small quantity of gas is preferred to prevent the electron stream emitted by the filament from spreading, and to keep it 55 as a small pointer. This transmitting apparatus is primarily based on the effect of photo-electric emission upon a stream or quanta of electrons, preferably thermo-electrons, and makes use of a stream or pointer 60 of such thermo-electrons emitted from a heated filament. The stream of electrons is produced by the filament cathode 3, which may be oxide-coated and is heated as described. After leaving the filament the electrons may 65 pass through the small aperture of the metal shield 6 which concentrates them into a thin stream so that they may pass through the tubular anode 5.

70 The movement of the pointer is controlled by electric fields applied to the plates 7 and 8. An electric field applied to the plates 7 will deflect the electron pointer in one direction and an electric field applied to the plates 8 will deflect the electron pointer in another direction, and as here illustrated, these two deflecting directions are at right angles to each other. The result is that at any instant the recording point forming the 75 end of the stream of electrons occupies a position on the photo-electric layer 9 which both in direction and distance from its normal position at the center is the result of the deflecting forces due to the differences of potential acting at that instant on the two pairs 80 of plates.

85 In addition to its deflection by an electric field, the electron stream can be deflected by a magnetic field by using outside of the tube either a permanent magnet or pair of coils 90 in which the current is flowing.

95 The picture which is to be transmitted is focused upon the layer 9 of photo-electric material, and if the layer 9 is semi-transparent, the picture or image may be focused right through the coating (lens 10 illustrated for that purpose). In case the layer 100 9 is thick enough to be opaque, the picture to be transmitted is focused upon the potassium or coating 9 on the side facing the electron

stream,—lens 11 illustrated being for that purpose.

With the picture focused through or upon the photo-electric coating 9, the first essential thing is to cover the entire picture with the electron stream in approximately 1/10th of a second, or greater i. e. a speed productive of direct vision. This may be accomplished by impressing electro-static variations from an alternating current on both the pairs of plates 7 and 8. The cycle of one current need not be greater than approximately 8 to 20 cycles. For illustrative purposes, I will describe the operation in connection with an alternating current of 10 cycles impressed on the plates 8.

The result of this impressed current on the plates 8 is that the electron pointer will go back and forth over the end 2 of the bulb and over the picture ten times per second, but only in a single line. Assuming a picture 6" x 6", and the condition that it is desirable to break up the picture into 100 different lines to the inch, that would mean that there would have to be 600 lines across the picture.

If the first electro-static field which is applied to the plate 8 causes the electron stream or pointer to traverse the picture ten times per second, then the electron pointer crosses the picture in 1/10th of a second. Now, in order to break this up into 600 parts, it is necessary to divide 600 by 1/10th, or in other words, an alternating current of 6000 cycles per second must be applied to plate 7. This alternating current of the required number of cycles may be produced in any suitable and well known manner, as for instance, by an audion oscillating system, whereas the alternating current applied to the plates 8 altho producible in various known ways, may be produced by an ordinary 10 cycle generator.

Under the conditions described, the entire picture focused on or through the coating 9 will be covered and broken up into fine lines in the necessary time to produce the desired results.

There are several circuits which can be used in obtaining modulation in this transmission of the picture focused on the coating 9. Perhaps the simplest form is that connecting the photo-electric coating 9 with the heated filament 3 or source of the electron stream. In the first instance, no additional source of potential will be inserted in this circuit, but it may contain the primary 12 of a transformer, the secondary of which may lead to suitable well known amplifying devices, or the coating 9 and the source of the electron stream 3 may be connected in circuit with the filament and grid of a properly biased audion bulb for amplification purposes, the methods of amplification and the required circuits being well known.

In the circuit just described, the switch

numbered 13 is left open, or that portion of the circuit is entirely omitted. The operation of this structure is as follows:—

The electrons of the moving pointer will explore every portion of the picture focused on the photo-electric material. The electrons will constitute the return electrical connection between the filament and the photo-electric material. The units of this exploring electron finger alternately are rushing towards first an illuminated portion of the photo-electric material, and next an unilluminated portion of the photo-electric material, there will as a result obtain different electrical phenomena in the completed circuit, due to the negative electrons approaching different potential points on the illuminated photo-electric electrode 9, and minute electric currents will flow in the complete circuit controlled by the illuminated potassium electrode.

It is at present my belief that this action is based on the law that when two dis-similar charges come in contact in a circuit, a minute current will flow,—contact electricity. In this manner, the picture is broken up and translated into consecutive electron pulses which are amplified, and may then be turned back into corresponding light fluctuations and when put back on a screen in the proper position at the receiving end will reproduce the picture focused on or through the photo-electric electrode at the sending end. In addition, these electron pulses impressed on an amplifying system at the sending end may be sent along wires or by wireless to the receiving end, all in a well known manner, should that be desirable.

The receiving apparatus may be in the form of a vacuum oscillograph substantially identical with the structure shown in Fig. 1 except that the end 2 of the bulb has a coating of a fluorescent material, such as a mixture of calcium tungstate and zinc silicate instead of a photo-electric material. The transmitted impulses at the receiving end may be impressed on the circuit which connects the filament with the cylinder and as the impulses increase or decrease, the intensity of the electron stream correspondingly increases and decreases, consequently the fluorescence increases and decreases in like manner, and the pattern traced in visible lines is photographically active. It is only necessary to put these changes in intensity resulting in changes in fluorescence in their proper position in order to re-form the picture focused on the coating 9 at the sending end. This is done by making the varying intensity electron pointer cover the fluorescent screen in the same manner and synchronized with the electron pointer at the sending end. This requires impressing 10 cycles on one of the pairs of plates in the receiving bulb, and 6000 cycles on the other pair.

It then only remains to make the phases of the similar cycles in the sending and the receiving apparatus the same. This is most easily accomplished by transmitting the same 5 cycle currents as used in the sending end over another pair of wires so that synchronism is obtained by using the identical current fields that produce the movement of the electron pointer in the sending bulb. However, other 10 methods may be used in synchronizing and separate fields may be used to produce the movement of the finger other than here described.

As an alternative arrangement, there may 15 be placed in the receiving bulb a grid large enough so that the electron pointer will always pass through it, and then the incoming current pulses may be impressed upon this grid to thereby control the current intensity 20 of the electron pointer which will correspondingly control the fluorescence of the coating corresponding to the coating 9. On the other hand, a small grid may be placed between the filament and the cylinder to control the intensity 25 of the electron pointer.

Altho the apparatus of Figure 1 may be utilized as above described without any extra potential in the circuit between the electrode 9 and the filament 3, it may perhaps be 30 preferable to place a potential in this circuit making the filament 3 negative and the photo-electric electrode 9 positive. This may be done by closing switch 13 and opening switch 14. In this case the electrons as they approach an illuminated portion or more negative 35 sphere of influence would, as a result of the tendency negative emission of the photo-electric material due to light, give a decreased current in this circuit and reverse- 40 ly an increased current where the electrons approach a non-illuminated or less negative sphere of influence of the photo-electric electrode.

If the photo-active material is made the 45 positive electrode there may not be an actual negative emission, but there will be a spot if illuminated that is negative in respect to a spot which is not illuminated.

Further, it may be advisable instead of 50 impressing a direct current on the filament photo-electric electrode circuit to impress an oscillating carrier current on this circuit. This may be effected in any suitable and well known manner. In this arrangement, the 55 oscillating carrier current will be likewise modulated as the negative electrons approach consecutive and either more or less negative spheres of influence in the photo-electric layer. In such case where an oscillating carrier 60 current is used quanta of electrons will be directed to the different parts of the photo-electric electrode 9, depending on the frequency of the pulsating carrier current, and this frequency may be determined empirically 65 for best results.

Instead of using a pulsating current, an alternating current may be impressed on this circuit, altho at present such arrangement seems less preferable. In case of pulsating direct current the photo-electric material 70 should be positive and the filament negative.

There are various other combinations and circuits which may be used, but all depend on the fundamental idea of obtaining modulation of a carrier current circuit depending 75 on the charge of the sphere of influence into which the thermo-electron pointer is converging at any one instant of time, which in turn depends upon the focusing of the picture on the photo-electric electrode or coating 9. In 80 addition, there may be amplification of the modulation so obtained and there remains only putting together again at the receiving end in terms of light and at the proper position to re-form the image and at a speed to 85 produce direct vision.

Obviously, a single picture may be transmitted or a series of pictures in sufficiently rapid succession to produce direct vision. In the latter case where a moving picture is to 90 be transmitted it would be preferable to employ a shutter arrangement at the sending end and possibly also at the receiving end in order to obviate any blurring. On the other hand, a chopper carrier current might be employed instead of the shutter.

In Figure 2 there is illustrated a large grid 15 interposed between the plate electrode 16 and the filament 3 and in the path of the electron stream or pointer which is indicated in dotted lines in the figures. This grid may be formed of any suitable material, and is full of very small holes and is coated with a photo-electric material. The picture to be transmitted is focused upon the photo-electric material deposited on the grid 15 and the holes of the grid should correspond to the points of the picture to be transmitted. As shown, the grid 15 is disposed in a plane substantially parallel with the end of the plane 2 of the bulb. The plate electrode 16 is connected in circuit with the filament 3, and this circuit may include the secondary of a transformer as described in connection with Fig. 1 or the electrodes may be connected to any amplifying means such as the grid filament circuit of an audion. In addition, the circuit connecting the plate 16 with the filament 3 need not include any source of potential or it may include a source of direct current —20— or a source of oscillating current, or a source of alternating current, all as described in connection with the analogous circuit of Figure 1.

The interposition of this special grid between the thermo-electric source and the plate may produce larger effects of the light upon the electron finger as the latter is directed to different portions of the grid, and a substantial control of the carrier current in the 125 130

plate filament circuit results. In this case the electron finger may spread on emerging from the grid and make no difference so long as it is point controlled at the grid on which the picture is focused.

5 In addition to the connections shown in the drawings, the grid 15 may have an electric connection to the outside of the bulb so as to permit of biasing the grid, if desired.

10 The structure of Figure 3 differs from Figure 1 in the interposition of a ring electrode 17 between the filament 3 and the photo-electric coating or electrode 9, and as illustrated the ring 17 is connected to the coating 9 by an 15 electric circuit including a source of potential 18 arranged in such a manner that the ring is positive and the photo-electric coating 9 is negative, thereby producing an actual emission of electrons. The introduction of 20 the exciting circuit between the coating 9 and the ring electrode 17 makes the spheres of influence of the photo-electric electrode more pronounced. This additional circuit between the ring 17 and the photo-electric electrode 25 9 may also be utilized in connection with the structure of Figure 2 in that the ring may be inserted between the grid 15 and filament 3 and may be connected in circuit with the photo-electric coating on the grid through a 30 source of potential in such a manner as to maintain the ring positive and the photo-electrode negative in the same manner as Figure 3, and for the same purpose of effecting more pronounced results.

35 Any suitable and known means may be utilized in the ordinary manner for applying an electric field of proper cycle to the plates 7 and 8, for instance, as described, a generator or an audion oscillating system. Altho I have 40 shown and described in a diagrammatic manner specific structures and arrangement of apparatus and the parts thereof, as instantiating embodiments of this invention, I do not desire to restrict myself to the details of the 45 structure or the specific method of operation described, as various changes may be made within the scope of the appended claims.

Picture as used in the claims hereof is deemed to include any picture, direct vision, 50 object or image that can be produced or be focused on the photo-electric layer, and focusing is deemed to include any suitable means of producing such picture on such coating.

I claim:—

55 1. The method of transmitting pictures, motion-pictures or direct vision comprising causing an electron stream to traverse the picture when the latter is focused upon a photo-electric material having a negative potential maintained thereon.

2. An apparatus for transmitting pictures, motion-pictures or direct vision, comprising a filamentary cathode, an anode of tubular form, a circuit connecting the cathode and the 60 anode, and including a source of potential,

means for deflecting the stream of electrons emitted by the cathode, a photo-electric layer over which said electron stream as deflected is adapted to pass and upon which the picture is adapted to be focused, and a circuit connecting the photo-electric layer and the 70 cathode.

3. An apparatus for transmitting pictures, motion-pictures or direct vision, comprising a filamentary cathode, an anode of tubular form, a circuit connecting the cathode and the anode, and including a source of potential, means for deflecting the stream of electrons emitted by the cathode, a photo-electric layer over which said electron stream as deflected is adapted to pass and upon which the picture is adapted to be focused, a circuit connecting the photo-electric layer and the cathode, and means for maintaining the 75 photo-electric layer negative.

4. An apparatus of the class described comprising an elongated bulb having a substantially flat end, a coating of photo-electric material on the interior of the flat end of said bulb, a cathode within the bulb, a tubular anode within the bulb arranged to direct the stream of electrons emitted by the cathode toward the said photo-electric coating, means for deflecting said stream of electrons in different directions and means for focusing a picture upon said photo-electric coating, and a circuit connecting the photo-electric coating and the cathode.

5. An apparatus of the class described comprising an elongated bulb having a substantially flat end, a coating of photo-electric material on the interior of the flat end of said bulb, a cathode within the bulb, a tubular anode within the bulb arranged to direct the stream of electrons emitted by the cathode toward the said photo-electric coating, means for deflecting said stream of electrons in different directions, and means for focusing a picture upon said photo-electric coating, a circuit connecting the photo-electric coating and the cathode, and means for impressing an electric current on said circuit.

6. An apparatus of the class described, comprising an elongated bulb having a substantially flat end, a coating of photo-electric material on the interior of the flat end of said bulb, a cathode within the bulb, a tubular anode within the bulb arranged to direct the stream of electrons emitted by the cathode toward the said photo-electric coating, an opaque disc having a small opening positioned between said anode and cathode, said opening being in line with the opening of the anode and the apex of the cathode, a pair of spaced parallel plates positioned between 115 said anode and said photo-electric coating, a second pair of spaced parallel plates having their plane surfaces at right angles to the plane surfaces of the first-named plates and positioned adjacent the same on the side of 120

the photo-electric coating, means for deflecting said electron stream by energizing said pairs of plates with a high and low frequency alternating current respectively means for focusing a picture upon said photo-electric coating, a circuit connecting the photo-electric coating and the cathode and means for impressing an electric current on said circuit.
